UNITED STATES PATENT OFFICE

EARL VERNON HILL, OF CHICAGO, ILLINOIS

DESIGN FOR AN AIR CONDITIONING UNIT

Application filed May 21, 1932. Serial No. 43,868. Term of patent 14 years.

To all whom it may concern:

Be it known that I, EARL VERNON HILL, a citizen of the United States, residing at Chicago, in the county of Cook and State of Illinois, have invented a new, original, and ornamental Design for an Air Conditioning Unit, of which the following is a specification, reference being had to the accompanying drawing, forming part thereof.

The figure is a perspective view of the air conditioning unit showing my new design,

upon which an air filter is superposed and forms a part thereof. The rear of the unit is plain and has a conventional vent for attachment to a duct of a heating element or air furnace.

I claim:

The ornamental design for an air conditioning unit, as shown and described.

In testimony whereof, I hereunto set my hand.

EARL VERNON HILL.
